UNITED STATES PATENT OFFICE.

JOHN W. GENTRY, OF OAKLAND, CALIFORNIA, ASSIGNEE OF TWO-THIRDS
TO G. A. LORING AND W. H. TERRY, OF SAME PLACE.

CABLE-GRIP.

SPECIFICATION forming part of Letters Patent No. 416,673, dated December 3, 1889.

Application filed May 7, 1889. Serial No. 309,926. (No model.)

To all whom it may concern:

Be it known that I, JOHN W. GENTRY, a citizen of the United States, residing at Oakland, in the county of Alameda and State of California, have invented new and useful Improvements in Cable-Grips; and I do hereby declare the following to be a full, clear, and exact description of said invention, reference being had to the accompanying drawings, and to the letters of reference marked thereon, which form a part of this specification.

My invention relates to gripping devices for cable railways.

15 The invention consists in a gripping device provided with stationary friction-rollers for holding the cable, with both the upper and lower gripping-jaws made movable, and to certain novel features in the construction and 20 arrangement of parts, all as hereinafter explained.

In the accompanying drawings, Figure 1 is a perspective view of the gripper frame or standard, showing the cable gripped by the 25 jaws. Fig. 2 is a vertical section of the frame with the operating lever and links connecting the same with the frames of the gripping-jaws removed. Fig. 3 is a transverse section on the line x x , Fig. 1. Fig. 4 is a perspective view of the lower end of the standard, showing one of the spindles on which one of 30 the cable friction-rollers is mounted. Fig. 5 is a perspective view of the lower gripper-jaw and its guide-frame. Fig. 6 is a perspective view of the upper gripping-jaw and its 35 guide-frame. Fig. 7 is a vertical transverse section of the lower clamping-jaw. Fig. 8 is a perspective view of the detachable gripper-face for the upper jaw. Fig. 9 is an enlarged 40 vertical section of one of the guiding pulleys or rollers.

The standard which supports the parts consists of the side frame A, made flaring for about one-half of its length and connected 45 at its upper end by the arching bar A', which forms the segmental rack, hereinafter referred to, and connected at its lower end by a cross-bar A², forming an open or skeleton frame.

The side frame-bars A for a portion of 50 their length, or that portion which is made straight, are each provided with a rib or flange a, to form a guideway for the guide-

frame C of the upper gripping-jaw. This frame is made in bow or inverted-U form, and has connected to its lower end the gripping-jaw C'. This gripping-jaw is made with a removable gripping-face C², connected to the main portion by means of ears formed thereon engaging sockets in the main portion and pins or bolts C³, passing through the same. 55

The inner and outer faces of the bow-frame are provided with ribs or flanges a', the outer ones to engage the ribs a on the frame-bars A and the inner ones to engage and form a guide or track for the clamp-frame D of the 60 lower jaw, which is provided with similar flanges a² to engage the same.

Upon the lower end of the frame D is mounted the lower gripping-jaw D', also provided with a removable gripping-face; but in 65 this case the gripping-face is secured to the main portion by means of tongue-and-groove or dovetail connection, and with a screw d to hold said parts together.

The gripping-faces of the jaws are made 70 removable, so that new faces can be substituted as the same become worn.

In suitable bearings formed with or secured to the upper gripper-jaw C' are mounted friction-rollers d', to prevent friction in passing 75 around curves. Similar friction-rollers d² are secured in suitable bearings on the opposite side in the standard A for a similar purpose.

Near the upper end of the frame A, adjacent to the segmental rack, are secured cross-bars E, and centrally of and between which is pivoted a rocking arm or walking-beam E', one arm of which is connected through suitable links with the frame C, while the other arm is connected to the frame D through 85 similar links. By the rocking of said arm or walking-beam is made to move the frames in such manner as to cause the gripping-jaws to move to or away from each other simultaneously. 90

The rocking arm or beam has connected to it a lever G, provided with a suitable hand-latch G', and which latch is adapted to engage the teeth of the segmental rack G² to hold the lever, and with it the gripping-jaws, 95 at any desired position.

On the lower end of the frame A are mounted friction-rollers H for guiding and forming a support for the cable to hold the same in 100

proper relation to be gripped by the moving jaws.

The gripper-frame is secured to the car through the perforated lugs I I, projecting 5 from the frame.

From the foregoing it will be seen that the gripping-jaws are made movable simultaneously and that the friction-rollers for supporting and holding the cable in proper relation to the gripping-jaws have a fixed relation relative to the frame.

Having now described my invention, what I claim, and desire to secure by Letters Patent, is—

15 1. In a gripping device for cable roads, the combination, with the supporting-frame having at its lower end grooved carrying-rollers, one at each corner, of the guide-frame arranged to slide in said supporting-frame and having 20 at its lower end a gripping-jaw and immediately above said jaw frictional rolls, the clamp-frame sliding in said guide-frame and provided at its lower end with a gripping-jaw, and means to actuate said jaw-carrying 25 frames, substantially as set forth.

2. In a gripping device for cable roads, the combination of the frames to which the grip-

ping-jaws are connected moving one within the other, the rocking arm or beam, the links connected to the rocking beam and to the 30 frames, and the lever for rocking the beam, substantially as set forth.

3. In a gripping device for cable roads, the combination of the gripper-frame provided with the movable gripping-jaws carrying the 35 friction-rollers, and the frame having the friction-rollers connected thereto on the opposite side to engage the groove and prevent friction in turning curves, as set forth.

4. In a gripping device for cable roads, the 40 combination of the supporting-frame provided with the ribs or flanges, the bow or inverted-U frame carrying one gripping-jaw mounted therein and provided with similar flanges on both its inner and outer faces, and 45 the central bar or frame carrying the other gripping-jaw adapted to move in the inverted-U frame, substantially as set forth.

In testimony whereof I affix my signature in the presence of two subscribing witnesses.

JOHN W. GENTRY. [L. S.]
